(57) **CLAIM**

The ornamental design for a notebook computer, as shown and described.

DESCRIPTION

FIG. 1 is a perspective view of a notebook computer showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the portion, labeled '9' of FIG. 1;

FIG. 10 is an enlarged view of the portion, labeled '10' of FIG. 2;

FIG. 11 is an enlarged view of the portion, labeled '11' of FIG. 3;

FIG. 12 is an enlarged view of the portion, labeled '12' of FIG. 7;

FIG. 13 is a perspective view of the notebook computer of FIGS. 1-8 shown in an alternate position;

FIG. 14 is a front view thereof;

FIG. 15 is a rear view thereof;

FIG. 16 is a left side view thereof;

FIG. 17 is a right side view thereof;

FIG. 18 is a top view thereof; and,

FIG. 19 is a bottom view thereof.

The evenly-spaced broken lines shown in the drawings illustrate portions of the notebook computer that form no part of the claimed design. The unevenly-spaced broken lines indicating areas of the figures shown enlarged form no
